UNITED STATES PATENT OFFICE.

FRANCIS M. BAKER, OF ST. LOUIS, MISSOURI, ASSIGNOR OF ONE-HALF TO
JAMES H. PENCE AND LOUIS L. KORTOS, BOTH OF SAME PLACE.

AWNING-BLIND HINGE.

SPECIFICATION forming part of Letters Patent No. 417,623, dated December 17, 1889.

Application filed October 15, 1889. Serial No. 327,081. (No model.)

To all whom it may concern:

Be it known that I, FRANCIS M. BAKER, of St. Louis, in the State of Missouri, have invented certain new and useful Improvements in Awning-Blind Hinges; and I do hereby declare the following to be a full, clear, and exact description of the invention, such as will enable others skilled in the art to which it appertains to make and use the same.

10 My invention relates to an improvement in awning-blind hinges.

The object is to provide a set of hinges which will admit of the outward swing of the lower end of the shutter, in addition to the ordinary opening swing of the shutter, without disturbing the engagement of the pintles in their sockets, and to further provide self-locking hinges of the above character in which the leaves of the hinge may be rigidly secured to the building and shutter, respectively.

With these ends in view my invention consists in certain features of construction and combinations of parts, as will be hereinafter described, and pointed out in the claims.

Figure 1 is a view of a set of the hinges adjusted for use with shutter closed, and looking toward the free vertical edge of the shutter. Fig. 2 is a similar view with shutter 30 swung outward at the bottom, forming an awning. Fig. 3 is a view with shutter swung wide open, the edge of the shutter secured to the hinges being now toward the point of observation; and Fig. 4 is a top plan view of one of the hinges.

A represents the stationary section of the leaf of the hinge which is to be fastened to the building, and A' represents the movable section of said leaf. The section A is provided with a vertically-extended flattened end a, which may be let into a recess formed in the casing, and is provided with screw-holes for fastening it in position. Its outer end is projected in the form of a flat tongue a', having vertical abutments a² at its inner end. In the upper hinge the abutments a² extend from the bottom edge of the tongue only a part of its width, to enable the section A' to tilt, as will hereinafter appear, while in 45 the lower hinge it preferably extends through-

out the entire width of the tongue, to form an extended bearing for the movable section A', and so serve to steady the shutter when the parts A A' of the hinge are in locked adjustment.

55 The section A' of the hinge is provided at its inner end with a recess B, the walls of which embrace the opposite sides of the tongue a'. (See Fig. 4.) The two sections are united by pins or bolts b, which extend laterally through the walls of the recess B and through the tongue a'. The pin or bolt b in the upper hinge acts as a pivot upon which the section A' may be rocked vertically, while the pin or bolt b in the lower hinge is made removable for effecting the separation of the two sections A and A' when it is desired to throw the lower end of the shutter outward. The section A' is further provided with a pintle b', uprising therefrom, and also with oppositely-inclined surfaces b² b³, located the one inwardly and the other outwardly from the base of the pintle, and with a depression b⁴ between the base of the pintle and the outer inclined surface b³, as portions of a self-locking device the principle of which is well known.

70 The leaf of the hinge which is fastened to the shutter is denoted by C. Its end c toward the shutter is extended vertically and provided with screw-holes for securing it firmly to the shutter, while its opposite end is provided with a socket D, to receive the pintle b', and with oppositely-inclined surfaces d and d', corresponding to the oppositely-inclined surfaces b² b³ on the section A', and adapted to engage therewith when the shutter is swung wide open. The depression b⁴, above referred to, allows the downwardly-projected portion d² of the 75 socket D to drop as the inclined surfaces on the parts A' and C register with each other.

80 When the parts are adjusted as shown in Figs. 1 and 3, the shutter may be swung around to open and shut as in ordinary hinges, and will, when swung wide open, lock itself in open adjustment by the engagement of the inclined surfaces above referred to.

85 When it is desired to swing the bottom of the shutter outward to form an awning, as 90

shown in Fig. 2, the pin or bolt b is first removed, and the bottom is then free to swing outward, the upper section A' turning on its pivot b , the pintle and socket in both upper and lower hinges remaining in their relative adjustments.

The inner end of the upper section A' has its upper corners rounded, as shown at b^5 , to free it from cramping against the upper end 10 of the abutments a^2 , and the pintle on the lower section A' is provided with a removable cap E or other abutment of any well-known or approved form to prevent the section A' from dropping out of position when 15 the same is released from the section A and the bottom of the shutter swung outward.

Both upper and lower hinges effectually prevent the sagging of the shutter by the engagement of the ends of the sections A and 20 A' with the lower portions of the abutments a^2 .

It is evident that any well-known and approved locking device might be substituted for the removable pin or bolt b , and that various other slight changes in the form and construction of the several parts might be resorted to without materially departing from the spirit and scope of my invention.

Having thus fully described my invention, 30 what I claim as new, and desire to secure by Letters Patent, is—

1. The combination, with a hinge-section adapted to be fixed to the building and a hinge-leaf adapted to be fixed to a shutter, of 35 an intermediate movable section having a pintle-and-socket connection with the shutter-leaf and a fastening for securing the in-

termediate section to the hinge-section at the building, substantially as set forth.

2. The combination, with an upper hinge 40 consisting of a leaf for attachment to a shutter, a section for attachment to a building, and an intermediate section having a pintle-and-socket connection with the section at the building, of a lower hinge consisting of a 45 leaf for attachment to a shutter, a section for attachment to a building, and an intermediate section having a pintle-and-socket connection with the shutter-leaf and a separable connection with the section at the building, 50 substantially as set forth.

3. The herein-described hinge, consisting of a leaf adapted to be fixed to a shutter and a sectional leaf, one section of the sectional leaf being provided with a vertical abutment, 55 and the other section having an engagement at one end with the said abutment and at its opposite end having a pintle-and-socket engagement with the shutter-leaf, substantially as set forth.

4. The herein-described hinge, consisting of a leaf formed in one piece and provided with a socket and a leaf formed in two sections, one fixed and the other movable, the movable section being provided with a pintle 65 and a removable abutment on the pintle, for the purpose substantially as set forth.

In testimony whereof I have signed this specification in the presence of two subscribing witnesses.

FRANCIS M. BAKER.
